UNITED STATES PATENT OFFICE.

ALEXANDER CAMPBELL, OF TYRRELL, OHIO.

TOY HORSE.

Application filed June 29, 1925. Serial No. 40,130.

The object of this invention is to provide a self-propelled animal mounted upon wheels in such a manner that when the rider bears his weight upon the saddle the front and rear wheels of the animal are caused to spread apart, and when the weight on the saddle is released the legs are drawn together, causing the animal to move forward.

Another object of this invention is to provide the legs of the animal with wheels provided with means for preventing a backward movement thereof so that the animal will have a positive forward movement upon each downward movement of the saddle caused by the placing of the weight thereon.

A further object of the invention is to provide means for adjusting the spring which draws the legs together, and whereby the tension of the spring can be increased to insure the positive drawing of the legs together.

A still further object of my invention is to provide a self-propelled toy of this character in which the front legs and head of the animal can be turned for guiding the same.

In the accompanying drawings:—

Figure 1 is a side elevation of my invention applied to a horse showing the body portion broken away to show the saddle operating means.

Figure 2 is a detail plan view showing the connection of the upper end of the leg operating levers.

Figure 3 is a transverse sectional view taken on the line 3—3 of Figure 1.

Referring now to the drawings, 1 represents the main body of the horse, or other animal, which is provided with a head 2, 40 having a neck portion 3 made separate and of an external diameter less than the body portion, and which is adapted to telescope within the body portion and leaving a space between the same. The neck portion of the 45 horse extends down to the point A as shown by a line indicating where the neck ends. Carried by the body portion 1 of the animal are the hind legs 9 which are carried by the yoke member 15 which is pivoted at 50 17 within the body of the animal and its forward end provided with a slot 26 through which passes the rod 24. The front legs of the animal as indicated at 8 are opposite the neck 3 of the animal and are carried by the 55 yoke shaped member 16, which is pivoted at 18 within the neck portion of the horse and

said yoke member 16 at its upper end is provided with a transverse slot 25 through which the rod 24 passes.

The rod 24, as shown in Figure 1 of the drawings, is carried by the saddle 14 and extends downwardly through the slots 25 and 26 and passes through the cup shaped member 20 carried at the lower end of the body portion. The lower end of the rod 24 60 below the cup shaped member 20 is screw threaded as indicated at 21 and upon which is screwed the adjusting nut 23, whereby the rod may be raised and lowered for a purpose hereinafter more fully described. Surrounding the rod 24 is a coil spring 19 65 which has its lower end bearing against the upper face of the cup shaped member 20, and its upper end bearing against the plate 21 which surrounds the rod and which in 70 turn bears against the upper end of the yoke 16. The front legs 8 have mounted therein rollers 10 on the shaft 12, and provided with ratchet teeth on one side thereof adapted to 75 be engaged by the pawl 13 which prevents any backward rotation of the wheels 10. The hind legs 9 have the wheels 11' mounted on the shaft 12' and the pawl 13' engaging the ratchet teeth carried by the side of the wheels to prevent any backward movement thereof. The body 1 of the horse has rigidly secured thereto bolts or rivets 6 and flat bars 4 and 5 which extend forwardly 80 into the neck portion of the animal. The neck portion 3 is provided with transverse plates 27 adjacent its upper end and with the transverse plates 28 adjacent its lower end, and between which the bars 4 and 5 extend. Passing loosely through the bars 4, and 5, and plates 27 and 28 is the rod 7, forming 85 a pivot whereby the neck portion 3 may be turned thereon, and due to the transverse slot 25 the yoke may be turned to allow the neck and front legs to turn within the body portion, whereby the animal may be guided. 90

From the foregoing description it will be seen that when the weight of the rider on the saddle 14 forces the rod 24 downwardly and engages the yokes 15 and 16 they are likewise forced downwardly against the tension of the spring 19 and the hind legs 9 of the animal are prevented from moving, due to the pawl 13', but the front legs 8 are moved forward and the whole animal has a tilting action or more of a squatting action. 105 When the weight of the rider is removed from the saddle 14 the coil spring 19 forces 110

the yokes 15 and 16 upwardly. The front wheels 10 are prevented from moving backward and the rear wheels 11 move forward causing the animal to have a forward rising 5 action to assure the position shown in Figure 1 of the drawings.

When it is desired to steer the animal the rider moves the neck portion 3 either to the right or left causing the same to swing on 10 the pivot 7 carrying with it the yoke 16 which in turn carries the legs 8, and causing the animal to be guided to either the right or left.

Having thus fully described my invention 15 what I claim is:—

1. A self-propelled toy comprising a body portion in the form of an animal, four legs pivoted to the body portion, a wheel carried by each leg, means for preventing the backward 20 rotation of the wheel, means operating by the weight of the rider for spreading the front and rear legs apart, and spring means for drawing the legs together when the weight of the rider is removed from the operating 25 means.

2. A self-propelled toy comprising a body portion in the form of an animal, front and rear legs arranged in pairs and pivoted to the body portion, wheels carried by the lower 30 ends of each of the legs, means for preventing the backward rotation of the wheels, a saddle, means operated by the downward movement of the saddle for spreading the front and hind legs apart, and spring means 35 for drawing the legs together when the weight is removed from the saddle.

3. A self-propelled toy comprising a body portion in the form of an animal, front and rear legs pivoted to the body portion, a wheel 40 carried by the lower end of each leg, means for preventing the backward rotation of the wheel, a saddle carried by the body portion and adapted to engage the legs beyond their pivotal connection with the body portion for 45 spreading them apart, and spring means for drawing the legs together when the weight is removed from the saddle.

4. A self-propelled toy comprising a body portion in the form of an animal, two intermediately pivoted yokes carried by the body 50 portion and carrying legs at their lower ends, a wheel carried by the lower end of each leg, means for preventing the backward rotation of the wheels, a saddle adapted to 55 engage the upper ends of the yokes and forcing them downwardly spreading the legs, and spring means for forcing the upper ends

of the yokes upwardly when the weight is removed from the saddle.

5. A self-propelled toy comprising a body portion in the form of an animal, two yokes intermediately pivoted within the body portion and carrying at their lower ends the front and hind legs of the animal, a wheel carried by the lower end of each leg, means 60 for preventing the backward rotation of the wheels, a saddle carrying a rod passing through slots in the upper ends of the yokes, said saddle adapted to engage the yokes and force them downwardly spreading the legs 65 apart, and a coil spring surrounding the rod and engaging the yokes for forcing the yokes 70 upwardly for drawing the front and hind legs together.

6. A self-propelled toy comprising a body portion, a neck portion pivotally mounted on a vertical pivot within the body portion, a yoke intermediately pivoted to the body portion and carrying the hind legs of the animal, a wheel carried by each of the legs, 80 means for preventing the backward rotation of the wheel, a yoke intermediately pivoted to the neck portion, front legs carried by the yoke, a wheel carried by each of the front legs, means for preventing the backward 85 rotation of said wheels, and a saddle adapted to engage the upper ends of the yokes beyond their pivots for forcing the same downwardly for spreading the legs, and spring means for forcing the yokes upwardly and forcing the legs together. 90

7. A self-propelled toy comprising a body portion, a neck portion pivoted within the body portion on a vertical pivot, a yoke pivoted to the body portion and carrying at 95 its lower end the hind legs of the animal, wheels carried by the hind legs, means for preventing the rotation of said wheels, the upper end of the yoke having a transverse slot therein, a saddle carried by the body 100 portion, a rod carried by the saddle passing downwardly through the longitudinal and transverse slots in the yokes, and a coil spring surrounding the rod and having its lower end bearing against the body portion 105 and its upper end against the yokes, whereby the weight of the saddle forces the upper ends of the yokes downwardly spreading the legs apart, and the spring forcing the upper 110 ends of the yokes upwardly and forcing the legs together.

In testimony whereof I affix my signature.

ALEXANDER CAMPBELL.
